(57) **CLAIM**

The ornamental design for a corner bookmark, as shown and described.

DESCRIPTION

FIG. 1 is a perspective view of the corner bookmark, showing my new design. The broken line depiction of a book is included for illustrative purposes only and does not form any part of the claimed invention.

FIG. 2 is another perspective view of the corner bookmark. FIG. 3 is a view of the right side elevation of the corner bookmark shown in FIG. 2.

FIG. 4 is a front elevation view of the corner bookmark shown in FIG. 2.

FIG. 5 is a rear elevation view of the corner bookmark shown in FIG. 2; and,

FIG. 6 is the left side elevation of the corner bookmark shown in FIG. 2.
